UNITED STATES PATENT OFFICE.

GEORG KRAUSS, OF GEORGSMARIENHUTTE, NEAR OSNABRUCK, GERMANY.

FLUSHING APPARATUS FOR WATER-CLOSETS WITH CLOSED FLUSHING BOXES.

Application filed April 1, 1927, Serial No. 130,142, and in Germany March 29, 1927.

Flushing apparatus for water closets with closed flushing box have become known in which the bottom valve of the water box is opened, after the opening of an auxiliary 5 valve, by water flowing in underneath a piston connected to said bottom valve.

This invention has for its object to improve the flushing box so that the construction of the same and of its auxiliary means is 10 considerably simplified and a secure function of the same is ensured.

The invention consists in mounting the bottom valve on a cylinder which is shiftable on a stationary piston, the water being 15 supplied underneath the cylinder bottom by the intermediary of a valve through the hollow piston rod.

The invention consists further in providing underneath the water supply to the shift- 20 able cylinder an outflow opening for re-tarding the closing of the bottom valve of the water box and for re-supplying air to the same after every flushing.

The invention may be carried out in vari- 25 ous manners. One embodiment of the in- vention is shown, by way of example, in the only figure of the accompanying drawing which shows the improved flushing appa- ratus in vertical section.

30 The water box *a* communicates with the water main *c* by a port *b*, and it is shut off by a bottom valve *d* from the collecting box *e*. The bottom valve *d* is fixed on a cylinder *g* shiftably mounted on a stationary piston *f*, said cylinder having a metal lining *h*. The cylinder *g* may be made of cast 35 iron, the stationary piston *f* and its hollow tubular piston rod *i* being made of brass. The bottom valve has at its lower end air 40 outlet channels *k*.

The stationary tubular piston rod *i* is connected at its rear end *e'* closed by a valve *l* to the water pipe *e* which has, underneath the piston rod, a narrow outflow channel *m*.

45 The valve *l* is connected with a rod *o* controlled by a spring *n* and operated by an oscillatable lever *q* which has a cam *p*. The water box *a* is fixed on a bracket *r* by means of a nut *s*.

The flushing apparatus for the water 50 closet acts so that, when the lever *q* is pulled, water can flow from below under the top plate *g'* of the cylinder which is lifted by the water pressure so that the bottom valve *d* is opened. The water flows then through 55 the passage *d'* into the collecting box *e* and thence through the outflow tube *t* by natural fall into the cistern. After the water has 60 flowed out, the cylinder can descend only gradually by gravity as the water which stands under the top plate *g'* of the cylinder 65 can flow out only slowly through the passage *m*. The closing of the bottom valve *d* is thus retarded and fresh air is supplied to the water box after every flushing, a perfect 70 functioning of the flushing apparatus being 75 ensured.

I claim:

1. A flushing apparatus for water closets with closed flushing box, comprising in combination with the water main, a water box, a stationary hollow piston in the bottom end of said water box, a cylinder shiftably mounted on said stationary piston, a bottom valve in said cylinder, a valve in said water main for supplying water through said hollow piston underneath the top plate of said cylinder to lift this cylinder and to open 80 said bottom valve, and a pull lever for operating said water supply valve.

2. A flushing apparatus for water closets with closed flushing box, comprising in combination with the water main, a water box, a stationary hollow piston in the bottom end of said water box, a cylinder shiftably mounted on said stationary piston, a bottom valve in said cylinder, a valve in said water main for supplying water through said hollow piston underneath the top plate of said cylinder to lift this cylinder and to open 85 said bottom valve, a pull lever for operating said water supply valve, and a narrow water outlet underneath the water supply to said shiftable cylinder for retarding the closing 90 of said bottom valve and for supplying fresh air to said water box after every flushing.

In testimony whereof I affix my signature.

GEORG KRAUSS.
